SCREEN ATTACHMENT

Filed Oct. 16, 1925

UNITED STATES PATENT OFFICE.

J. T. HUNTINGTON, OF FLINT, MICHIGAN.

SCREEN ATTACHMENT.

Application filed October 16, 1925. Serial No. 62,720.

Ordinarily a screen is placed in the inner guideway of a window frame so that the lower sash may be lowered on to the upper edge of the screen. Some times the sash prevents rattling of the screen in the guideway. Other times the screen supports the sash if it is not properly hung in the window frame, and in either instance engagement of the sash with the screen is adapted to prevent flies, insects and foreign matter from passing between the screen and sash. This practice necessitates removing the screen when the sash is to be lowered, as in inclement weather, and my invention aims to provide means whereby the screen may be positioned in the outer guideway of the window frame and held by the sash to exclude flies, insects, and the elements other than through the screen. Ordinarily a comparatively thin sectional, extensible screen is used, particularly of less width than the guideway of a window frame, and for such screen I have devised an extensible member that may be fitted over the upper edge of the screen to extend into the plane of the lower sash, whereby said sash may be lowered to engage the member and retain the screen in a set position. From this position the screen may be shifted, without removal from the window frame, to permit of the sash being closed.

My invention will be hereinafter specifically described and then claimed, and reference will now be had to the drawing, wherein

Figure 1 is a front elevation of a portion of a window frame having a screen provided with an attachment in accordance with this invention;

Fig. 2 is a vertical cross sectional view taken on the line II—II of Fig. 1 showing the screen positioned so that the lower sash may engage the attachment;

Fig. 3 is a similar view showing the screen shifted so that the lower sash may be closed;

Fig. 4 is a perspective view of the screen attachment, and

Fig. 5 is a similar view of a portion of an attachment having sash engaging prongs.

In the drawings, the reference numeral 1 denotes a window sill having a frame 2 constructed to provide an outer guideway 3 and an inner guideway 4, these guideways

being ordinarily separated by a parting strip 5. The guideways 3 and 4 ordinarily accommodate sashes and the lower sash has 55 been designated 6.

The reference numeral 7 denotes, by the way of an example, an extensible screen which is ordinarily placed in the guideway 4 so that the lower sash 6 may be lowered 60 on to the upper rail or frame 8 of the screen, but instead of following out this usual practice, I intend to place the screen 7 in the guideway 3. With the screen of less width than the guideway it may be shifted laterally therein and in one position, as will hereinafter appear provides clearance for a closing movement of the sash 6 and in another position permits of the sash holding the screen 7 against or in proximity to the parting strip 5.

The screen attachment comprises two telescopic members 9 and 10, each inverted channel shaped in cross section with an outer wall 11 of less depth than an inner wall 12 of the member. The inner walls 12 of the members 9 and 10 are formed with lateral flanges 13 and 14 respectively, and the lateral flange 13 of the inner member 9 has a return bend 15 affording a guide and retaining means for 80 the lateral flange 14 of the outer member 10. As a result of this construction the inner and outer members 9 and 10 are held in adjoining telescopic relation so that the longitudinal dimension of the attachment may be increased or decreased at will to adapt the attachment to screens of various lengths.

The attachment is adapted to fit over the upper rail or frame 8 of the screen 7 and the members of said attachment are adjusted 90 relative to each other so as to extend from one parting strip 5 to the other. When the attachment is correctly positioned on the screen the flanges 13 and 14 afford a lateral support and with the screen 7 against the parting strips 5 of the window frame the lower sash 6 may be lowered on to the lateral support of the attachment to hold the screen in position and at the same time form a seal between the screen and sash to exclude the elements, bugs and insects.

As shown in Fig. 3 the screen 7 may be shifted outwardly whereby the attachment provides clearance for a closing movement

of the sash 6, thus obviating the necessity of removing the screen from the window frame when the sash is to be closed.

As shown in Fig. 5, the return bend portion 15 of the inner member 9 may be provided with outstruck prongs 16 to engage in a bottom rail of the lower sash 6 and thus prevent the attachment from shifting relative to the lower sash should the pressure of the sash fail to hold an attachment devoid of prongs or their mechanical equivalent.

From the foregoing it will be observed that I have devised means for positioning a screen relative to a window sash modified from the usual practice, of placing the screen below the sash and lowering the sash on to the screen, by setting the screen in a plane to one side of the sash, and then mounting a member on the screen to extend into the path of the lower sash so that said sash may be lowered to engage the member and provide a connection between the offset screen and the sash.

Obviously the telescopic members 9 and 10 will be made of non-corrodible material or finished to withstand the elements and at the same time harmonize with the finish of the screen or window frame. The configura-

tion of the telescopic members is susceptible to such changes as are permissible by the appended claims.

What I claim is:—

1. A screen attachment comprising telescopic longitudinally extensible members, each member having the configuration of an inverted channel provided with a lateral flange, the flange of one member having a return bend to form guiding and retaining means for the flange of the other member.

2. A screen attachment as called for in claim 1, wherein each member has its flange equipped channel wall of greater depth than the other channel wall.

3. A screen attachment comprising longitudinally extensible members one slidable on the other, said members having a configuration to fit over the upper edge of a screen and provide a lateral sash engaging support in a plane below the upper edge of the screen by which the screen may be held in a set position.

4. A screen attachment as called for in claim 3, wherein the sash engaging support has prongs adapted to engage in the sash.

In testimony whereof I affix my signature.

J. T. HUNTINGTON.
